LIQUID APPLICATOR

Rose M. Breeze, Medford, Oreg.

Application December 7, 1951, Serial No. 260,359

4 Claims. (Cl. 132—109)

This invention relates to liquid applicators, and more particularly to an applicator for applying liquids, such as hair-waving and neutralizing solutions, to hair.

It is among the objects of the invention to provide an improved applicator which can be conveniently held in one hand and used to apply liquid, such as hair-waving solution, to tresses of hair guided by the other hand of the person using the applicator; which has mutually opposed liquid-applying bodies detachably mounted thereon, so that the bodies can be squeezed together to regulate the amount of liquid carried thereby and avoiding spilling or dripping of the liquid, and can be removed from the applicator for cleaning or replacement when desired; which maintains the user's hands substantially free of the liquid; which may utilize various accessories, such as combs, brushes, pads and rollers for applying the liquid to the hair; and which is simple and durable in construction, economical to manufacture, easy to use, and neat and attractive in appearance.

Other objects and advantages will become apparent from a consideration of the following description and the appended claims in conjunction with the accompanying drawing, wherein:

Figure 1 is a side elevational view of a liquid applicator illustrative of the invention;

Figure 2 is a top plan view of the applicator illustrated in Figure 1;

Figure 3 is a transverse cross-sectional view on the line 3—3 of Figure 1;

Figure 4 is a fragmentary longitudinal, cross-sectional view on the line 4—4 of Figure 2;

Figure 5 is a perspective view of the opposed liquid-applying devices without the applicator by which they are normally carried; and

Figure 6 is a perspective view of a modified form of liquid-applying device mountable in the applicator.

With continued reference to the drawing, the applicator comprises a pair of elongated members 10 and 11 crossed over intermediate their length and having looped handles 12 and 13, respectively, at one side of the location at which they cross over, and flat, mutually opposed jaws 14 and 15 at the other side of the cross-over location. The intermediate portions of the members between the looped handles and the corresponding jaws are inclined to both the handles and the jaws, as illustrated in Figure 1, so that when the handles and jaws are substantially parallel to each other, the intermediate portions together constitute a geometrical figure in the shape of an X.

The intermediate portions of the members 10 and 11 are flattened and are disposed in side-by-side relationship, and a pivot pin or screw 16 extends through these intermediate portions at the cross-over location and pivotally connects the members together.

The jaws 14 and 15 are also flattened and disposed with their flattened surfaces substantially parallel to the axis of the pivot pin 16 and hollow receptacles 17 and 18 of rectangular shape and each having one open side are disposed between the jaws 14 and 15 and secured medially of the width thereof one to each of the jaws is coterminous relationship to each other and with the open side of each receptacle adjacent to and facing the open side of the complementary receptacle. The two receptacles 17 and 18 are of substantially the same size and shape and are elongated in the direction of the length of the members 10 and 11, and each receptacle

2

has internal recesses, as indicated at 19 and 20, disposed one in each end wall thereof.

In the arrangement illustrated in Figures 1 to 5, inclusive, a brush 21 is detachably mounted in the receptacle 18, and a pad 22 of absorbent material and combs 23 and 24 are detachably mounted in the receptacle 17 in a manner such that the bristles of the brush are disposed between the combs and opposed to the pad 22.

10 The brush has a back 25 of elongated, rectangular shape which closely fits into the receptacle 18 and has detents, as indicated at 26, projecting one from each end thereof and resiliently engaged in the recesses 20 in the end walls of the receptacle 18 to detachably secure the brush in the receptacle, and bristle tufts 27 projecting perpendicularly from the face of the back 25 adjacent the open side of the corresponding receptacle at locations spaced apart over the area of the corresponding face of the back.

20 The combs 23 and 24 have backs 28 and 29 respectively disposed against the inner sides of the side walls of the receptacle 17, and teeth 30 and 31 projecting perpendicularly from the backs 28 and 29 and out of the open sides of the receptacle 17, these teeth being disposed at respectively opposite sides of the brush 21.

25 The pad 22 is a rectangular body of suitable absorbent material, such as natural or synthetic sponge, and is disposed between the comb backs 28 and 29 and between the portions of the comb teeth adjacent the backs. The comb backs 28 and 29 are joined at their ends by transverse walls 32 and 33 to provide a rectangular structure which fits into the receptacle 17 and in which the pad 22 is secured by suitable means, such as the tongues 34 and 35 which project inwardly from the end walls 32 and 33 into the ends of the pad. The end walls 32 and 33 carry outwardly extending detents 36 and 37 which are frictionally engaged in the recesses 19 provided in the end walls of the receptacle 17 to releasably secure the comb and pad assembly in this receptacle.

30 It is to be noted that the brush 21 which is detachably mounted in the receptacle 18 and the combs 23 and 24 which are detachably mounted in the receptacle 17 constitute rigid structures detachably disposed in the receptacles 18 and 17 respectively, and the pad 22 constitutes a liquid applying means carried by the rigid structures and disposed at least partially outwardly of the corresponding receptacles.

35 With this arrangement, and with the implements held by the handles 12 and 13, the brush 21 and comb and pad structure may be immersed in a container of liquid, such as hair-waving or neutralizing solutions, to saturate the pad with the liquid. The implement may then be removed from the liquid and the handles pressed together to press the brush against the pad and press some of the liquid out of the pad, the implement simultaneously shaken to remove adhering drops of liquid therefrom. The pressure on the handles is now relieved, permitting the pad to expand, and, since the pad is now somewhat less than saturated, none of the liquid will be spilled or will drop from the applicator. The handles 12 and 13 are then moved apart and a strand of hair is brought through the combs and placed over the exposed face of the pad 22 at the scalp end of the tress. The brush, pad and combs are then moved outwardly from the scalp along the tress of hair, pressure being exerted on the handles to gradually force the liquid from the absorbent pad onto the hair as the hair passes by the pad. The proper amount of liquid can be applied to the hair without any excess which would cause dripping or running of the liquid.

40 In the arrangement illustrated in Figure 6, a pair of absorbent rollers 40 and 41 are utilized instead of the brush 21 and pad 22. The roller 40 is mounted in a frame 42 formed of sheet material and including a flat intermediate portion 43 of rectangular shape and end tabs 44 and 45 disposed one at each end of the intermediate portion and projecting from the same side of the intermediate portion substantially perpendicularly thereto. The tabs 44 and 45 are provided each with an aperture near the end thereof remote from the intermediate portion 43, and suitable arbors, as indicated at 46,

extend one from each end of the roller 40 coaxially of the roller and through the apertures in the corresponding tabs 44 and 45 to journal the roller in the frame 42. The intermediate portion 43 of the frame is of a size and shape to closely fit into one of the receptacles 19 or 20, and the tabs 44 and 45 carry outwardly projecting detents, as indicated at 47, which resiliently engage in the recesses in the end walls of the corresponding receptacle to releasably secure the frame and roller in the receptacle.

The roller 41 is mounted in a frame 48 having an intermediate portion 49 of elongated, rectangular shape dimensioned to fit into the other receptacle, and end tabs 50 and 51 which extend perpendicularly from the same side of the intermediate portion 49 one at each end of the latter and in which the roller 41 is journaled by suitable arbors, as indicated at 52, disposed one at each end and coaxially thereof. The end tabs 50 and 51 of the frame 48 carry outwardly projecting detents, as indicated at 53, which resiliently engage in the recesses in the end walls of the corresponding receptacle to releasably secure this frame in the receptacle.

The roller-applying devices, as illustrated in Figure 6 and described above, may be utilized in the same manner as the brush and pad for applying liquid to tresses of hair.

It is to be understood that various other means may be provided for applying the liquid to the hair, such as, for example, bodies of absorbent material, such as absorbent cotton, placed one body in each of the receptacles 17 and 18, absorbent sponges placed one in each of the receptacles, a body of absorbent material in one receptacle and a roller or a body of non-absorbent material in the other, and that the combs may be provided or omitted, as may be desired.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. An applicator for applying liquid to tresses of hair comprising a pair of elongated members crossed over intermediate their length and pivotally connected together at their cross-over location to provide a pair of opposed jaws at one side and a pair of opposed handles at the opposite side of said cross-over location, hollow receptacles disposed between said jaws in parallel relationship to each other and secured one to each of said jaws and each having an open side facing the other receptacle, rigid structures embodying a coating brush and comb detachably secured one at each of said receptacles, and liquid applying means carried by said rigid structures and disposed at least partially outwardly of the open sides of the corresponding receptacles for receiving tresses of hair therebetween and applying liquid to the hair.

2. An applicator for applying liquid to tresses of hair comprising a pair of elongated members crossed over intermediate their length and pivotally connected together at their cross-over locations to provide a pair of opposed

jaws at one side and a pair of opposed handles at the opposite side of said cross-over location, receptacles of elongated rectangular shape disposed between said jaws and each having an open side opposed to the other receptacle, said receptacles being elongated longitudinally of said jaws and said jaws being secured to the corresponding receptacles medially of the width thereof, rigid structures detachably disposed one in each of said receptacles, and liquid applying means carried by said rigid structures and disposed at least partially outwardly of the corresponding receptacles for receiving tresses of hair therebetween and applying liquid to the hair.

3. An applicator for applying liquid to tresses of hair comprising a pair of elongated members crossed over intermediate their length and pivotally connected together at their cross-over location to provide a pair of opposed jaws at one side and a pair of opposed handles at the opposite side of said cross-over location, receptacles of elongated rectangular shape disposed between said jaws and each having an open side opposed to the other receptacle, said receptacles being elongated longitudinally of said jaws and said jaws being secured to the corresponding receptacles medially of the width thereof, rigid structures detachably disposed one in each of said receptacles, and liquid applying means carried by said rigid structures and disposed at least partially outwardly of the corresponding receptacles for receiving tresses of hair therebetween and applying liquid to the hair, said receptacles having recesses in the inner surfaces of the end walls thereof and said rigid structures having detents on the ends thereof resiliently engaged in the corresponding recesses to releasably secure said rigid structures in said receptacles.

4. An applicator for applying liquid to tresses of hair comprising a pair of elongated members crossed over intermediate their length and pivotally connected together at their cross-over locations to provide a pair of opposed jaws at one side and a pair of opposed handles at the opposite side of said cross-over location, receptacles of elongated rectangular shape disposed between said jaws and each having an open side opposed to the other receptacle, said receptacles being elongated longitudinally of said jaws and said jaws being secured to the corresponding receptacles medially of the width thereof, rigid structures detachably disposed one in each of said receptacles, and liquid applying means carried by said rigid structures and disposed at least partially outwardly of the corresponding receptacles for receiving tresses of hair therebetween and applying liquid to the hair, at least one of said liquid applying means comprising a compressible body of liquid absorbent material.
